Charles D. Gooding.

UNITED STATES PATENT OFFICE.

LLOYD B. SALT, OF DEDHAM, MASSACHUSETTS.

SIGNALING INSTRUMENT.

1,302,715.

Specification of Letters Patent.

Patented May 6, 1919.

Application filed December 24, 1917. Serial No. 208,531.

To all whom it may concern,

Be it known that I, LLOYD B. SALT, a citizen of the United States, residing at Dedham, in the county of Norfolk and State of Massachusetts, have invented new and useful Improvements in Signaling Instruments, of which the following is a specification.

This invention relates to improvements in signaling instruments and has for its object 10 to provide a simple, compact and handy instrument for signaling with the international or Morse telegraph codes by means of light flashes or sound waves, said instrument being particularly adapted for use in 15 instructing pupils in the art of sending and receiving telegraph messages.

The invention consists in the combination and arrangement of parts set forth in the following specification and particularly 20 pointed out in the claim.

Referring to the drawings:

Figure 1 is a plan view of an instrument embodying this invention, portions thereof being shown in section.

25 Fig. 2 is a section taken on the line 2—2 of Fig. 1.

Fig. 3 is an end elevation of the same.

Fig. 4 is a plan view of a portion of the device shown in Fig. 1, illustrating a buzzer 30 attached thereto in place of the usual electric lamp.

Like numerals refer to like parts throughout the several views of the drawings.

In the drawings, 1 indicates what is generally known as an electric pocket flash light which embodies in its construction a battery container 2, the present form being cylindrical. 3 are batteries arranged within said container, said batteries being of the usual 40 well known type and having contact surfaces 4 and 5 at opposite ends thereof. At one end of the container 2 an electro-receptive device is arranged in the form shown in Fig. 1. This device embodies an electric 45 lamp 6 which has screw threaded engagement with a partition 7 inserted adjacent to one end of said container and said lamp has electrical connection with the battery nearest thereto and also with said partition 7, said 50 partition being, in turn, electrically connected, by means of a conductor 8, with a metal ring 9 secured to the opposite end of said container.

A metal closure or cap 10 has screw 55 threaded engagement with the metal ring 9 and is readily removable therefrom to per-

mit the insertion of batteries or the removal thereof from said container. Secured to the closure 10 is a bracket 11 provided with ears 12 and 13 which are tapped to receive screws 60 14, said screws being arranged with their axes alining.

The adjacent ends of said screws are preferably cupped to receive correspondingly shaped members 15 and 16 upon a lever 17 65 and thereby pivotally support said lever upon said bracket. The lever 17 has an arm 18 which is bent to extend over the edge of the closure 10 and carries an adjustable stop screw 19, the end of which is arranged to 70 engage the side of said closure and limit the pivotal movements of said lever in one direction.

Another arm 20 is arranged to extend for a portion of its length, as at 21, parallel 75 with the end of the closure 10 and this portion is adapted to support an adjustable contact screw 22 which limits the pivotal movements of said lever in the other direction. Beyond the contact screw 22 the arm 80 20 is bent at 23 in a direction substantially at right angles to the portion 21 of said lever and substantially parallel with the axis of the cylindrical container 2, said last named portion being disposed near the lower edge 85 of the closure 10 in close proximity to the surface upon which the container 2 is placed.

A foot piece 24 is attached to the closure 10 adjacent to the last named extension of the arm 20, for the purpose of preventing 90 the container from rolling upon the surface wherein the same is resting. At the outer end of the arm 20 a finger piece 25 is attached. The lever 17, consisting of the arms 18 and 20 and the finger piece 25, constitutes a telegraph key which, upon being rocked about its axis, consisting of the screws 14, moves the contact screw 22 into electrical connection with the batteries contained within said container, and the preferred medium whereby such a connection is produced is a contact member 26 secured to the closure 10 and insulated therefrom by an insulating bushing 27, said contact member being in alinement with the end of 95 the screw 22 and adapted to be engaged thereby when the key is depressed.

When the key is rocked about its axis to move said contact screw 22 in engagement with the contact member 26, a light spring 110 28, attached to the bracket 11 and engaging said lever 17, will be deflected and when

the pressure is released from said key said spring acts to return the same to its normal position, that is, with the adjusting screw 19 in engagement with the closure 10.

- 5 In Fig. 4 I have shown, in the end of the container 2 in place of the lamp 6, a buzzer 30 which is of a well known construction and this buzzer is mounted upon a base 31 which is provided with an extension 32 constructed 10 preferably of insulating material provided with a sleeve 33 of metal, which is screw threaded to fit the lamp socket in the partition 7. The sleeve 33 is connected, by means of a conductor 34, with a binding post 35, 15 supported upon the base 31 of said buzzer and having electrical connection with the electro-receptive device of said buzzer and this device being old and well known to those skilled in the art, no further description 20 is thought necessary.

The end of the extension 32 has a contact member 36 mounted therein and insulated from the sleeve 33, said contact member 36 being adapted to engage the end of the battery 3 within the container adjacent to said frame 7, and extending from the contact member 36 to a binding post 37 mounted upon said base 31 is a conductor 38 which is also electrically connected with the electro-receptive device of the buzzer, thus it 25 will be seen that when the telegraph key is operated by pressure upon the finger piece 30 to move the contact screw 22 into en-

gagement with the contact member 26 and the electric circuit including the battery 35 within said container is made, the buzzer will be operated to transmit the message indicated by sound waves and in like manner the device will be operated when the lamp is inserted in place of said buzzer to 40 indicate, by flashes of light, the message that is ticked off by the key.

Having thus specifically described my invention what I claim and desire by Letters Patent to secure is:

An instrument of the class described having, in combination, a container, a battery arranged in said container, an electro-receptive device disposed at one end of said container, a detachable cap for the other end of said container, a U-shaped bracket secured to said cap, a telegraph key pivotally mounted between the arms of said bracket and extending laterally from said cap, adapted to be operated to close the electric circuit containing said battery and said electro-receptive device, and a spring adapted to return said key to its normal position to break said electric circuit.

In testimony whereof I have hereunto set 60 my hand in presence of two subscribing witnesses.

LLOYD B. SALT.

Witnesses:

CHARLES S. GOODING,
SYDNEY E. TAFT.
